UNITED STATES PATENT OFFICE.

RALPH L. BRAY, OF LONG BRANCH, NEW JERSEY.

LAUNDRY-EDGER.

No. 880,714

Specification of Letters Patent. Patented March 3, 1908.

Application filed November 5, 1906. Serial No. 342,103.

To all whom it may concern:

Be it known that I, RALPH L. BRAY, citizen of the United States, residing at Long Branch, in the county of Monmouth and State of New Jersey, have invented certain new and useful Improvements in Laundry-Edgers; of which the following is a specification.

Laundered articles and particularly such as are starched and comprise a number of layers of goods, after being ironed, require the opening of the button holes in order to admit of the buttons being passed readily therethrough, and, moreover, the edges are rough particularly this is the case with collars, cuffs, shirt and wristbands after the same have been laundered a number of times.

This invention provides a device which admits of quickly smoothing frayed or rough edges of collars, cuffs and the like and of opening button holes so as to admit of easily passing the buttons therethrough.

In the accompanying drawings forming a part of the specification: Figure 1 is a perspective view of a laundry edger and button hole opener embodying the invention. Fig. 2 is a longitudinal sectional view through the device. Fig. 3 is a detail view showing the application of the invention. Fig. 4 is a detail perspective view, showing the device used for smoothing the edge of a collar when worn.

Corresponding and like parts are referred to in the following description and indicated in all the views of the drawings by the same reference characters.

The device comprises a body or stock 1 which is provided at one end with a blade 2 and in its sides with a series of grooves 3. The blade and body are preferably formed of a single piece, however, if preferred the blade 2 may be fitted to the body in any manner. The blade tapers in width and thickness to a point approximating the outline of a spear head. The end of the body adjacent to the blade 2 is made rounding so as not to injure the goods when using the device. The body 1 is of rounded form and is slightly tapered to present a neat appearance and enable the device to be conveniently grasped when used. The end opposite to the blade 2 is enlarged and made rounding, as shown at 4.

The grooves 3 are adapted to smooth the

edges of collars, cuffs, shirt-bands and the like when the device is passed over the edges thereof with the roughened edge arranged in a selected groove, as indicated most clearly in Fig. 3. It is to be understood that when passing the device over the edge to be smoothed it is given a rotary movement to bring all parts of the annular groove into contact with the edge, and a slight pressure is brought to bear so as to lay the projecting points which would be likely to cause irritation and to present an unsightly appearance. Attention is directed to the fact that owing to the rotary movement of the stock the grooves 3 have a frictional engagement with the projecting points which assists in properly laying the same instead of merely compressing them. The grooves 3 may be of like formation, but in order to increase the scope of usefulness of the article it is preferred to have the grooves of different size according to different thicknesses of goods or the kind of edge to be formed.

The edger and button hole opener herein disclosed may be constructed of any material such as celluloid, metal, wood or the like and may be finished in any way and be of any size.

It frequently happens that a collar, when worn, irritates by reason of projecting points. The present device may be utilized to smooth down the projecting points by applying the rounded flattened end 4, as indicated in Fig. 4, the rounded end 4 being passed over the edge or roll of the collar and bearing against the neck which serves to hold the device in proper position while passing it around the collar from one end to the other.

Having thus described the invention, what is claimed as new is:

As a new article of manufacture, the herein described hand operated laundry edger comprising an elongated cylindrical stock 1 having a plurality of annular edging grooves 3 formed therein toward one end, the opposite end serving as a handle for rotating the tool and applying it to the edge of a laundered article.

In testimony whereof I affix my signature in presence of two witnesses.

RALPH L. BRAY. [L. S.]
